CLAIM

The ornamental design for a tripod head, as shown and described.

DESCRIPTION

FIG. 1 is a front, left and top perspective view of a tripod head showing our new design;

FIG. 2 is a rear, right and bottom perspective view thereof;

FIG. 3 is a front elevational view thereof;

FIG. 4 is a rear elevational view thereof;

FIG. 5 is a left view thereof;

FIG. 6 is a right view thereof;

FIG. 7 is a top plan view thereof;

FIG. 8 is a bottom plan view thereof;

FIG. 9 is an enlarged view of a portion labeled as 9 on FIG. 1; and,

FIG. 10 is an enlarged view of a portion labeled as 10 on FIG. 1.

The long dash-dot broken lines in FIGS. 1 and 9-10 depict the bounds of the enlargements and form no part of the claimed design.

1 Claim, 10 Drawing Sheets
